Primary Examiner — Kevin K Rudzinski*Assistant Examiner* — Paul D Bohannon(74) Attorney, Agent, or Firm — Stetina Brunda Garred & Brucker(57) CLAIM

The ornamental design for an outdoor wing chair, as shown and described.

DESCRIPTION

FIG. 1 is a front perspective view of the outdoor wing chair of the present invention;

FIG. 2 is rear perspective view of the present invention;

FIG. 3 is a front view of the present invention;

FIG. 4 is a left-side view of the present invention, the right side being a mirror image thereof;

FIG. 5 is a rear view of the present invention;

FIG. 6 is a bottom view of the present invention; and,

FIG. 7 is top of view of the present invention.

In FIGS. 1-7, the tonal difference seen in the backrest represents a contrast in appearance.

1 Claim, 7 Drawing Sheets(56)
